LOOM FILLING CARRIER TIP SUPPORT

Henry Jones Lanier, Langdale, Ala.

Application March 18, 1937, Serial No. 131,701

8 Claims. (Cl. 139—251)

This invention relates to an attachment for a loom which has for its purpose to support the tip of a filling carrier during positioning of the same in the shuttle, to prevent undue slackness in the filling thread and to prevent breaking of the filling thread at transfer.

A specific embodiment of the attachment which constitutes my invention is illustrated in the drawing in which:

10 Figure 1 is a sectional view in elevation showing the relation of the parts at the time of replenishment of the filling.

Figure 2 is an enlarged plan view showing the shuttle and filling carrier tip support extending 15 through the feeler slot.

Figure 3 is an enlarged elevational view of the tip support attached to the filling parting means, and

20 Figure 4 is an enlarged perspective view of the tip support.

The filling carrier tip support of this invention is shown in combination with the loom replenishing mechanism disclosed in the Stafford Patent No. 1,585,218, but it is to be understood 25 that it is not limited in any respect to this particular type of loom.

In brief, the replenishing mechanism comprises as disclosed in Figure 1, a magazine 1 of the rotary type provided with the usual means for 30 supporting the filling carriers 2, a transerrer 3 positioned at the base of the magazine 1 adapted to transfer a filling carrier 2 from the magazine 1 to the shuttle 4 and to eject the exhausted filling carrier and filling parting means 5. The 35 replenishing mechanism is connected as usual to a train of mechanism controlled by a feeler finger. The lay 6 is provided with a shuttle box 7 at the replenishing end thereof, adapted to house the shuttle at the end of its flight, the forward wall 40 of the shuttle box being slotted to provide an opening opposite the feeler slot 8 of the shuttle when the latter is in replenishing position.

Referring more particularly to Figure 2, the filling parting means 5 is shown provided with 45 an adjustable stop 9, the end of which, by contact with the lay 6, limits the movement of the filling parting means. The adjustable stop 9 provides a convenient means for attaching the filling tip support 10 to the filling parting means 5.

50 Figures 3 and 4 disclose the filling carrier tip support 10, comprising a bowed wire including two sloping legs 11 and 12 connected by a horizontal bight 13, one leg 12 of the bow terminating in an eye 14 and the other leg 11 sloping forwardly 55 away from the plane of the leg 11 and bight 13

and having a horizontal extension at its lower end which is perpendicular to the aforesaid plane, the extension being inclined inwardly and upwardly at 15 for a portion and finally terminating in a portion 17 perpendicular with respect to 5 the plane of the leg 11 and bight 13 and provided at its free end with an upwardly facing concavo-convex tip 18.

The tip support 10 is attached to the filling parting means by means of the adjustable stop 9 10 and lock nut the shank of the stop passing through the eye 14 of the filling tip support and the lock nut abutting the outer face of the same, the bow bridging the filling parting means 5, the leg 11 sloping upwardly toward the filling parting means, 15 the bight 13 passing horizontally across the filling parting means and the leg 12 sloping downwardly away from and forwardly of the filling parting means. The downwardly and forwardly sloping leg 12 at substantially the medial line of the filling parting means 5 is bent substantially at right angles to the plane formed by the leg 11 and bight 13, and extends outwardly therefrom for a portion 15 of its length parallel to and spaced from the filling parting means. The provision of the 20 inclined portion at 16 directs the wire to a point adjacent to the tip 18 of the filling parting means at the upper edge and at that point, it continues horizontally outward at 17, the free end terminating about one and one-half inches in advance of 25 the tip 18 of the filling parting means. As previously stated, the free end portion 17 of the wire is provided with an upwardly facing concavo-convex tip 18.

In operation, as soon as the feeler finger indicates that the filling carrier is exhausted, the replenishing mechanism will be set in operation to transfer a filled filling carrier 2 from the magazine 1 to the shuttle 4 and to eject the empty filling carrier. This operation takes place 30 during the brief period that the shuttle 4 is boxed at the transfer end of the lay 6 and while the lay therefore approaches its full forward position. As the lay 6 beats-up into its full forward position, the filling parting means 5 enters 40 the feeler slot 8 in the usual manner, but preceded in this instance by the free end portion 17 of the wire which rides over the top of the exhausted filling carrier due to the slightly convex under side 18 at the tip and to the natural 45 resiliency of the wire which allows the same to deflect from its normally horizontal position. Concurrently, the transerrer mechanism comes into play and ejects the exhausted filling carrier 50 downwardly through the bottom of the shuttle 4. 55

The filling carrier 2 transferred from the hopper 1 necessarily enters the shuttle 4 above the end portion 17 of the wire and the tip 20 of the filled filling carrier 2 rests on and is supported by the 5 concave end portions 18 of the wire, thus tending to prevent the tip 20 of the filled filling carrier 2 from falling or being forced below the level of the line of the shuttle eye 21.

Immediately upon the proper seating of the 10 filled filling carrier 2 in the shuttle 4, the lay 6 beats back, the wire and filling parting means are withdrawn, and the loom continues its operation until the filling carrier is again exhausted.

The configuration and disposition of the wire 10 is such that in its operation as a tip support, 15 it does not interfere with the thread of the emptying filling carrier which is being ejected but serves to guide the thread into the filling parting means 5. In an automatic loom, it is necessary 20 that the filling parting means catch, hold and cut the thread of the emptying filling carrier to prevent the thread from being pulled back into the cloth by the returning shuttle, particularly in instances where pulled-in thread is objectionable. 25 Frequently, the filling thread is displaced above or below the line of the filling parting means, and is not caught by the filling parting means.

In order to overcome this, it is common in practice to set the filling parting means at a low 30 angle so that its tip is slightly below the normal line of the thread. Such a setting insures the catching of a sagging thread, but if the thread is slightly above its normal line, it may elude the filling parting means and not be caught and cut. 35 It is this latter condition which applicant's wire cures. The presence of the wire 10 guides the thread into the jaws of the filling parting means. It is apparent from Figure 3 that the wire 10 slopes upwardly from the tip of the filling parting 40 means, the free end 18 being at a substantially higher level than the jaws of the filling parting means and, therefore, it would pass over the top of a slightly upwardly displaced thread as it moves into the shuttle. When the new filling 45 carrier is disposed in the shuttle, it depresses the tip 18 of the wire 10 as indicated in Figure 1 and, as a result, the thread of the emptying filling carrier, which is beneath the wire 10, slides along the undersurface of the wire into the jaws of the 50 filling parting means.

In addition to serving as a guide, the wire 10 provides sufficient tension in the filling thread of the filled filling carrier to accomplish positive threading up. In the automatic replenishing 55 loom the filled filling carriers are disposed in a magazine, the ends of the threads from the filling carriers being attached to a thread holding plate. When the transfer is made a filled filling carrier moves from the magazine down into the shuttle 60 and as a result a certain amount of thread is pulled from the end of the filling carrier. If too much of the thread is pulled off at this time, there will be considerable slackness in the thread. Such a condition is not desirable because, in the 65 threading up of the shuttle, unless the thread lies across the shuttle eye under considerable tension, it will not thread itself. Various means have been provided in the nose of the shuttle to engage the thread in order to obtain the desired tension in the thread. In the present case, the tip 18 of the wire 10 rests against the lower surface of the filled filling carrier during the period 70 of transfer and threading up. The wire 10 being constructed of a resilient material, the tip 18 presses against the surface of the filling carrier

with a fair degree of pressure and thereby acts to prevent the filling thread from running off the end of the filling carrier too freely. As a result, the tendency toward slackness is eliminated and the shuttle threads up properly.

The wire 10, in addition, operates as a shuttle feeler in connection with the usual shuttle feeler. Double shots occur from the breaking of the filling and as the filling breaks frequently at the time of transfer, it is quite apparent that if the breaking can be eliminated at transfer, the objectionable feature of double shots will be in part eliminated. Breaking occurs when the shuttle is improperly boxed at transfer. If the shuttle is improperly boxed, the tip of the wire 10 will strike 15 the side wall of the shuttle, thereby preventing further forward movement of the filling parting means. As is usual in this type of loom, anything which prevents the filling parting means from moving forward will prevent the latch finger from 20 engaging with the bunter, thereby making it impossible for the loom to transfer.

Such changes from the particular construction here shown as are within the range of mechanical skill may, of course, be made without 25 departing from the spirit of the invention.

I claim:

1. In a bobbin changing loom operating with a shuttle having a bobbin therein, a filling parting means for the shuttle, and means carried by said 30 filling parting means to support the tip of the filling carrier during the positioning of the filling carrier in the shuttle.

2. In a bobbin changing loom operating with a shuttle having a bobbin therein, a filling parting 35 means for the shuttle, and means yieldably mounted with respect to said filling parting means to support the tip of the filling carrier during the positioning of the filling carrier in the shuttle.

3. In a bobbin changing loom operating with a shuttle having a bobbin therein, a filling parting means for the shuttle, and yielding means fixed to said filling parting means to support the tip of the filling carrier during the positioning of 45 the filling carrier in the shuttle.

4. In a bobbin changing loom operating with a shuttle having a bobbin therein, a filling parting means for the shuttle, and yielding means fixed to the filling parting means to extend substantially parallel to and past the free end of the same to support the end of the tip of the filling carrier during the positioning of the filling carrier in the shuttle.

5. In a bobbin changing loom operating with a shuttle having a bobbin therein, a filling parting means for the shuttle, and yielding means fixed to the filling parting means to extend substantially parallel to and past the free end of the same, the outer end of said means being arranged 60 to extend through the shuttle feeler slot during transfer of a carrier to engage and support the tip of the latter during its positioning in the shuttle.

6. A filling carrier tip support comprising a 65 bowed wire, one leg of the bow terminating in an eye and the other leg extending at right angles to the plane of the bow a substantial distance, and being provided at its free end with an upwardly facing concave tip.

7. A filling carrier tip support comprising a bowed wire, including two sloping legs connected by a bight, one leg of the bow terminating in an eye and the other leg extending perpendicularly to the plane of the bow, then sloping in- 75

wardly and upwardly for a portion and finally terminating in a portion perpendicular with respect to the bow and provided at its free end with an upwardly facing concavo-convex tip.

5 8. In combination, a filling parting means for loom shuttles, and yielding means fixed to the filling parting means, said means comprising a wire provided with an eye whereby it is attached to said filling parting means, a bow bridging the
10 filling parting means including a leg sloping up-

wardly toward the filling parting means, a bight extending horizontally across said filling parting means, and a leg sloping downwardly away from and forwardly of said filling parting means, the downwardly sloping leg being bent at the medial 5 line of the filling parting means at right angles to the plane of the upwardly sloping leg and bight and extending parallel to the filling parting means to a point substantially in advance thereof.
